UNITED STATES PATENT OFFICE

GEORGE W. PARIS, OF ROCHESTER, NEW YORK, ASSIGNOR TO KARLE LITHOGRAPHIC COMPANY, OF ROCHESTER, NEW YORK

COLLAPSIBLE AND REDUCING BOX

Application filed July 3, 1928. Serial No. 290,157.

This invention relates to improvements in folding, reducing and collapsible boxes. An object of this invention is to provide a box having a plurality of weakening, scoring or slotted lines positioned thereon in such a manner that the sides of the box will collapse and permit the upper portion to telescope over the collapsed section after it has been separated along the scoring lines.

10 A further object of this invention is to provide a box adapted particularly for small quantities of articles or food such as cough drops and the like, wherein portions of the box may be separated from the main body 15 section as the cough drops are consumed and re-located in relationship with the main body portion of the box, so as to form a complete package of a reduced size for accommodating the amount of unconsumed cough drops or the 20 like.

Other objects of this invention will appear from the following detailed description of the device, and as disclosed in the drawings which are herewith made a part of this application.

In the drawings—

Figure 1 illustrates a perspective view of the box showing its different portions in folded and closed relationship, and the score lines both longitudinal and peripheral located thereon.

Figure 2 represents a perspective view of the container showing a portion removed therefrom just previous to a reduction in size 35 of the container.

Figure 3 illustrates a perspective view of the container in a reduced form, the separated portion having been located in position.

Figure 4 discloses a perspective view of a further reduction in size of the container.

Figure 5 represents a sectional elevational view of the box or container.

Figure 6 illustrates a vertical sectional view of the container in a reduced form, a section 45 having been separated from the main body portion and telescopically arranged thereover.

Figure 7 represents a sectional view of Figure 6 along line 7—7.

Figure 8 illustrates a vertical sectional

view of Figure 4 disclosing the box further reduced in size over the disclosure in Figure 6.

Figure 9 represents a plan view of a single piece of material disclosing the box or container in unfolded position.

The collapsible and reducing package or box, according to this invention, is preferably made from a single piece of material, such as cardboard, and having side portions 1, 2, 3, and 4 adapted to be folded along score lines 5, 6, 7 and 8.

The side portions 1 and 2 are formed having end portions 9 and 10 attached thereto along the score lines 11 and 12. Closing flaps 13 and 14 are connected along score lines 15 and 16 to the end portions 9 and 10.

Tab members 17, 18, 19 and 20 are connected along score lines 21, 22, 23 and 24 to the side members 3 and 4. A tab member 25 is connected along the score line 8 to the side 2 so that when the sides of the box are brought into folded relationship along their various score lines a sufficient amount of material comprising the tab 25 may be provided for securely fastening by means of paste or otherwise to the side portion 3, thereby forming a box having open ends which may be closed when desired by the turning inward of the tab members 17, 18, 19, and 20 and the end portions 9 and 10, together with the closing tabs 14 and 15.

In order to provide a box having efficient means for collapsing and separating one portion from another when it is desired to reduce the size thereof, slotted or score lines 85 of a sufficient number such as designated by the numerals 26 and 27 are formed in the sides of the box, and deep score lines 28 and 29 are formed in the sides 3 and 4 of the box and longitudinally thereof in such a manner that 90 when one portion of the box is separated from another, for instance, along the line 27, the other portion may be easily collapsed so that the separated section can be brought down telescopically over the outer surface of the 95 box, thereby functioning to reduce the size of the container to a point which will accommodate the desired contents.

This invention provides a very efficient box or container adapted for holding vari-

ous articles of merchandise or otherwise, such as candies, in small quantities, which during the consumption thereof naturally require a reduction in the size of the box in proportion to the quantity consumed or disposed of, by merely separating a portion of the box along the peripherally arranged score lines and telescopically rearranging the separated section over the main body portion of the box, any desired reduction in size of the container may be accomplished.

It will be understood that many changes and modifications may be made in the form of embodiment of this invention within the scope of the following claims without departing from the spirit of the invention.

What I claim is:

1. A container formed in separable sections defined by score lines arranged peripherally of said container, a face of said container being divided longitudinally by a score line intersecting said peripheral score lines whereby one section when torn off, can be telescoped over another section by depressing the part of said face embraced in said other section along said longitudinal score line thereby narrowing the width of said other section.

2. A container formed in separable sections defined by score lines arranged peripherally of said container at different levels, a face of said container being divided longitudinally by a score line intersecting said peripheral score lines whereby one section when torn off can be telescoped over any of the other sections by depressing the part of said face embraced in said other section along said longitudinal score line, thereby narrowing the width of said other section.

40 In testimony whereof I affix my signature.
GEORGE W. PARIS.
